(57) **CLAIM**

The ornamental design for a left and right handed basting brush, as shown and described.

DESCRIPTION

FIG. 1 is a bottom perspective view of the present invention, showing the left and right handed basting brush new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a front elevational view partially in cross section through the spoon area thereof;

FIG. 9 is an enlarged cut away cross section showing a groove in the outside spoon area thereof; and,

FIG. 10 is an enlarged elevational cross sectional view cut away of the connection between the spoon cup and the support ring thereof.
